UNITED STATES PATENT OFFICE.

JOHN B. MUNSON, OF SCRANTON, PENNSYLVANIA.

COMBINED BABY-JUMPER AND CHAIR.

SPECIFICATION forming part of Letters Patent No. 561,908, dated June 9, 1896.

Application filed April 3, 1895. Serial No. 544,359. (No model.)

To all whom it may concern:

Be it known that I, JOHN B. MUNSON, a citizen of the United States, residing at Scranton, in the county of Lackawanna, State of Pennsylvania, have invented certain new and useful Improvements in a Combined Baby-Jumper, Chair, Crib, Hammock, and Carriage-Body, of which the following is a description, reference being had to the accompanying drawings and to the letters of reference marked thereon.

My invention relates to an improvement in baby-jumpers, and particularly to a combined baby-jumper and chair, the parts of which may be so adjusted as to render it capable of use as a crib, an invalid's chair, or hammock, and which may be also arranged to serve as a carriage-body for attachment to the springs and framework of an ordinary baby-carriage. In its use as a hammock, invalid's chair, baby-jumper, or crib it is capable of a vertical springing motion as well as a lateral swing.

The object of my invention is to provide a single article of furniture which by certain manipulations can be converted into any one of the various articles above referred to, as well as to provide a device which may be readily folded up and packed in a small space.

The invention consists, broadly, of a baby-jumper composed of a number of sections adapted to fold one within the other and capable of adjustment to various angles and relations one to another, whereby said article is capable of the variety of uses mentioned.

In the accompanying drawings, which illustrate the invention, Figure 1 is a perspective view showing the baby-jumper used as a chair. Fig. 2 is a view showing my invention as forming a crib when changed from the position assumed by the parts when used as a baby-jumper. Fig. 3 is a detail of one of the corner-irons, and Fig. 4 is a detail of the leg-secur ing device. Fig. 5 is a perspective view of my invention complete when adapted to be used as a baby-jumper.

Referring to the drawings, the frame of my improved baby-jumper consists of a seat portion, a back portion pivotally secured thereto, and a foot portion, also pivotally secured thereto and adapted to be adjusted with respect to each other. The seat portion consists of the side pieces A A and the cross-

piece B, the cross-piece being connected to the side pieces by means of the angle-irons or brackets a a, which have the upwardly-projecting pieces b secured or riveted into the side pieces and the horizontally-extending projections c secured or riveted to the bottom piece, these angle-irons affording a firm support for the cross-piece and firmly connecting the same to the side pieces. Each of these angle-pieces is formed with a loop d and a hooked projection e for the reception of the upper end of a leg C, which has a notch f formed in one side of it for the reception of a cam E, pivoted to said angle-piece, which cam holds the leg firmly in position, the legs, with the foot-piece, hereinafter described, affording a support for the seat when the apparatus is used as a chair. The rear end of said angle-iron is formed with a horizontally-projecting lug, adapted to fit a slot formed in the lower end of the angle-irons F, which secure together the sides G and cross-piece H of the back piece of the apparatus shown at I.

The particular connection between the side pieces G and the side pieces A, as above shown, consists of the slot h and a nut-and-bolt connection, which latter consists of the washer i, having two lugs adapted to fit the slot g and prevent said washer from turning, and having a recess j, in which the nut k on the end of the bolt is countersunk when in position. The shank of the bolt adjacent the head is squared to receive the thumb-wheel m, by means of which the parts are loosened or tightened, as desired. The upper ends of the angle-irons F are provided with enlarged heads having slots to receive lugs formed upon the ends of angle-irons K, which are secured to the piece L, forming a top for the back piece of the device, this top being hinged to the back piece by means of the slots and lugs referred to. Said hinged piece is adapted to be secured in its closed position by means of hooks n, pivoted to the side pieces G and adapted to engage eyes o, formed in lugs p, projecting from the angle-irons K down through the hinged top. This hinged piece, it will be seen, may be readily removed by detaching the hooks from the eyes and raising the lugs out of the slots.

In order to suspend the device to adapt it for use as a suspended baby-jumper, ham-

mock, or invalid's chair, I provide the side pieces G with ears q, and also the side pieces I with ears r, and secure to the ears q r, respectively, upon either side of the apparatus, 5 bails s, having eyes at their upper ends, between which eyes extends a cross-bar t, having a central eye, which is adapted to be suspended from a spring-support M in any suitable manner, preferably by means of a chain 10 having removable links with hooked ends adapted to be removably secured together. The ears are formed with a substantially triangular slot to give room for the passage of the end of a strap for holding the infant on 15 the seat without said strap interfering with the proper attachment of the bails. The ears q are of similar construction in case it is desired to use a strap across the breast of the infant when the apparatus is used as a crib 20 or invalid-hammock. The foot portion is composed of the side pieces O, the rear cross-piece P, and the bottom cross-piece Q, the side pieces O having segmental portions overlapping the side pieces A of the seat portion, 25 said side pieces O having slots g and being pivotally and adjustably secured to the side pieces A in the same manner that the back portion is secured to the seat portion. Angle-irons, as in the former cases, are used for securing the bottom, side, and back pieces of the foot portion together, and the upper ends of said angle-irons (herein shown at u) are provided with lugs adapted to fit in and be pivoted to slots in the forward ends of the 30 35 angle-pieces a, the curved slots and screw-bolt acting to guide said foot portion and to secure it in positions to which it may be adjusted.

To use the device as a baby-jumper, the 40 parts are adjusted to the position shown in Fig. 1 and suspended from the spring-support. When adapted to be used as a chair, it may be released from the spring-support, when the legs and foot portion act to keep it 45 steady on the floor.

When it is desired to use the device as a crib, an invalid's chair, or hammock, either suspended or not, all that is necessary to do is to loosen the fastening devices g and swing 50 the head and foot portions on their pivots until they are either in a straight line or at any desired angle with the seat portion, when the nuts are tightened.

When it is desired to use the apparatus as 55 a carriage-body, the parts may be adjusted to the position desired, and by means of a bolt

and nut the angle-irons a are secured to the supporting-springs of the carriage.

Having thus described my invention, what I claim, and desire to secure by Letters Pat- 60 ent, is—

1. In the herein-described combined chair, baby-jumper &c. a seat portion provided with side pieces having curved slots, a back portion having side pieces with segmental portions overlapping the side pieces of the seat portion, said back portion being pivoted to the seat portion, a bolt passing through said side pieces of both rear and seat portions, a washer to receive the bolt having lugs fitting 70 in the slots of the side pieces of the seat portion and having a recess to receive the nut upon the end of the bolt, and a thumb-piece for adjusting said bolt; substantially as described. 75

2. The herein-described baby-jumper, chair and crib comprising a central seat portion as A A B provided with slotted side pieces having curved slots, a back portion I having side pieces with segmental portions overlapping the side pieces of the central portion, said back portion being pivoted to the seat portion, a bolt passing through said side pieces of both rear and seat portions, a washer to receive the bolt, having lugs fitting in the slots 85 of the side pieces of the seat portion and having a recess to receive the nut upon the end of the bolt, and a thumb-piece for adjusting said bolt, a foot portion also having slotted side pieces with bolts passing through the side pieces of the seat portion engaging the slots in the side pieces of the foot portion, said foot portion being pivoted to the seat portion, and adapted when lowered to form a front support for said seat portion, and removably secured to the rear of said seat portion; substantially as described. 95

3. In the herein-described baby-jumper, a seat portion including an angle-iron provided with a loop and a hooked lug, a leg having a notched upper end fitting within said loop and beneath the lug, and a cam pivoted to said angle-iron and adapted to engage the notch in the upper part of the leg; substantially as described. 100 105

In testimony whereof I affix my signature in presence of two witnesses.

JOHN B. MUNSON.
